INORGANIC PHOSPHATE COMPOSITIONS, AND METHODS FOR THE PREPARATION AND UTILIZATION THEREOF

Joe S. Metcalf, Dayton, Ohio, assignor to Monsanto Chemical Company, St. Louis, Mo., a corporation of Delaware

Application April 16, 1954, Serial No. 423,552

11 Claims. (Cl. 252—135)

This invention relates to inorganic phosphate compositions. More specifically, it relates to tripolyphosphate and pyrophosphate compositions which have a relatively low rate of precipitation or crystallization from aqueous solution. The invention also relates to methods for producing the aforementioned phosphate compositions. In its more general aspects, the invention relates to methods for controlling the rate of precipitation or crystallization of phosphates from aqueous solutions. The invention is particularly useful in connection with the manufacture of detergent compositions by spray drying techniques.

Many detergent compositions, and especially those of the dry granular type, such as those designed for home laundry use, are made up of a multiplicity of components. Such components usually include, *inter alia*, a so-called "active" ingredient, such as a sulfated or sulfonated alkylated aromatic hydrocarbon or a condensation product of ethylene oxide with a long chain alkyl alcohol or mercaptan, a predominant proportion of a so-called "builder" such as sodium tripolyphosphate or tetrasodium pyrophosphate, and a small amount of a corrosion inhibitor such as the inorganic silicates, *e.g.*, sodium metasilicate, etc.

One of the problems in formulating a satisfactory and commercially useful granular mixture of several dry ingredients is to obtain a satisfactory uniformity of distribution of each of the separate ingredients throughout the bulk of the mixture. Failure to obtain such uniformity will increase the probability that small portions withdrawn from the bulk of the mixture will have a composition substantially different from the overall composition of the total bulk. Another problem in the formulation of such mixtures is to obtain a satisfactorily uniform particle size distribution of the ingredients. Failure to obtain this latter uniformity will give rise to a sort of automatic classification process whereby the coarse and fine particles tend to separate from each other during the transportation and handling of the packaged or bulk solids.

One of the ways in which the aforementioned difficulties are overcome, or at least minimized, is by the process, known as spray drying. In such a process a slurry of the solids in water is broken up into relatively uniformly sized droplets by atomizing the slurry. The droplets are then passed into or through a heated zone wherein the water is evaporated from each of the droplets, leaving discrete dry granular particles or agglomerates. By proper control of the conditions under which the spray drying is carried out, it is possible to obtain a reasonably uniform distribution of particle sizes, with each of the individual particles containing approximately the same proportions of the various components.

One of the factors which is particularly important in the control of a spray drying process is that of the viscosity, or consistency, of the slurry which is to be atomized. If the slurry is too thick or viscous, proper atomization thereof will be very difficult. In such a case the

fluidity of the slurry can be increased by increasing the amount of water in the slurry. However, an increase in water content is undesirable since a larger quantity of slurry must be handled, and a larger quantity of water must be evaporated, for a given output of detergent composition. Thus, it can be seen that it is very advantageous to have the solid content of the slurry as high as possible while still maintaining the required degree of fluidity for adequate atomization of the slurry.

As was indicated above, sodium tripolyphosphate and/or tetrasodium pyrophosphate are often used as a predominant component of granular detergent compositions prepared by spraying drying processes. The commercial tripolyphosphate and pyrophosphates utilized in such processes are usually in anhydrous form. When these anhydrous phosphates are put into an aqueous slurry, there is a marked tendency for the slurry to increase rapidly in consistency, and even set up as a completely non-fluid mass. This increase in consistency or loss of fluidity is at least partially caused by the reduction of free water content of the slurry because of the hydration of the anhydrous phosphates. The loss of fluidity of the slurry may also be accentuated by the manner in which crystal growth of the hydrates occurs. Because of the foregoing adverse effects of the anhydrous phosphates, and in order to maintain the slurry in a satisfactorily fluid state, it is necessary either to increase the water concentration of the slurry or to find a way to prevent or delay the precipitation or crystallization of the hydrates of these phosphates.

Accordingly, it is an object of the present invention to provide a method for decreasing the rate of crystallization of certain phosphates from aqueous solutions thereof. Another object of the invention is to provide a novel phosphate composition which is particularly useful in the formation of high fluidity slurries suitable for spray drying operations. It is a further object of the present invention to provide suitable methods for making such phosphate compositions. An additional object is to provide a novel method for forming slurries of phosphates which are highly suitable for spray drying processes. Other objects will be readily apparent from the following description.

It has now been found that the rate of precipitation or crystallization from aqueous solution of sodium phosphates having a molar ratio of $\text{Na}_2\text{O}/\text{P}_2\text{O}_5$ between about 5/3 and about 2, inclusive, can be substantially reduced by the presence in the solution of minor amounts of linearly polymeric phosphate ions having more than three phosphorous atoms in the linear chain thereof. It has also been found that a highly suitable phosphate composition having the property of reduced rate of precipitation from aqueous solution can be prepared by intimately dispersing a water-soluble linearly polymeric phosphate of the above-type throughout a particulate mass of the aforesaid sodium phosphates. It has also been found that such phosphate compositions are particularly useful in the preparation of detergent slurries suitable for spray drying to form granular detergent compositions. Typical of the linearly polymeric phosphates suitable for use in the various aspects of the present invention are the sodium phosphate glasses, *i.e.*, the amorphous compositions having $\text{Na}_2\text{O}/\text{P}_2\text{O}_5$ molar ratios between 1 and 1.67. As has been pointed out in various literature references (see, for example, Van Wazer, J. R., *Journal of the American Chemical Society*, 72, pp. 644-647 and 647-655 (1950)), these phosphate glasses are mixtures of water-soluble, straight-chain, polymeric materials made up of alternating atoms of oxygen and phosphorus. These mixtures of linearly polymeric phosphates can be characterized in terms of an average chain length, n .

The term "chain length," as applied to these straight chain polymeric phosphates, refers to the number of phosphorus atoms in the straight chain polymer.

As is also pointed out by Van Wazer, the average chain length of the mixture of polymers in a sodium phosphate glass is primarily a function of the ratio of $\text{Na}_2\text{O}/\text{P}_2\text{O}_5$ in the melt from which the glass was formed. The predominant polymer in such a mixture has a chain length equal to the whole number most closely approaching the value of the average chain length. The proportions of the other chain length polymers in the mixture become progressively smaller as the chain length increases or decreases from the average chain length. The average chain length of the glasses becomes increasingly greater as the ratio of $\text{Na}_2\text{O}/\text{P}_2\text{O}_5$ decreases ranging from a chain length of three when the $\text{Na}_2\text{O}/\text{P}_2\text{O}_5$ ratio equals $5/3$ to a chain length of several thousands or more as the ratio of $\text{Na}_2\text{O}/\text{P}_2\text{O}_5$ approaches unity.

As indicated previously, the linear polymers suitable for use according to the present invention are those having a chain length greater than 3. As the length of the chain increases, the polymers become more effective for purposes of the present invention. Thus, polymers having a chain length of 4 are more effective than those having chain lengths of less than 4. Likewise, polymers having a chain length of 5 are more effective than those having a chain length of 4, polymers having a chain length of 6 are more effective than polymers having a chain length of 5, and so on. A preferred class of linearly polymeric phosphates are those having an average chain length greater than about 10. While the effectiveness increases as the chain length increases, the rate of increase of effectiveness with respect to increase in chain length decreases as the chain length increases. Examples of particularly desirable linearly polymeric phosphates are the commercially available sodium phosphate glasses having molar ratios of $\text{Na}_2\text{O}/\text{P}_2\text{O}_5$ of about 1.1, about 1.4 and about 1.55.

The foregoing description stresses the importance of sodium phosphate glasses in the practice of the present invention because such glasses are very well known and more widely available than some of the other sources of linearly polymeric phosphate ions. However, it should be understood that any material which can supply the polymeric phosphate ion is a suitable source. Examples of other suitable materials are Kurrol's salt (a water-soluble, crystalline linearly polymeric potassium metaphosphate), lithium phosphates having a molar ratio of $\text{Li}_2\text{O}/\text{P}_2\text{O}_5$ between 1 and $5/3$, linearly polymeric ammonium phosphates formed either by replacing alkali metal ions with ammonium ions or by reaction of ammonia and P_2O_5 (with or without water), and the like. Also satisfactory are the acids corresponding to the foregoing salts. In order to affect the rate of crystallization of the tripoly- and pyrophosphates, it is necessary that the linearly polymeric phosphate ions be in solution. Consequently, any salts which are used as a source of such ions must be soluble in the tripoly- or pyrophosphate solution, at least to the extent of the minimum effective concentration of the ion.

As indicated above, the effectiveness of the linearly polymeric phosphates increases with increasing chain length of the phosphates. When these linearly polymeric phosphates are utilized with tripolyphosphates, the effectiveness also varies somewhat with the crystalline form of the tripolyphosphate. As is well known, sodium tripolyphosphate exists in two different crystalline forms—one known as the high temperature form (or Form I), and the other known as the low temperature form (or Form II). A preferred embodiment of the present invention is the use of the above-described polymeric phosphates with sodium tripolyphosphate-II, or with mixtures of Form I and Form II containing more than about 75 weight percent of the Form II material. Best results are obtained when using mixtures containing less than about

10 percent by weight of Form I, or even less than 5 percent by weight of Form I.

Because of the marked change in effectiveness of the polymeric phosphates with respect to both the chain length of the polymers and the crystalline form of the phosphates to which the polymers are added, the minimum effective concentration of the polymeric phosphates will vary over a rather wide range. In general, at least about 0.01 weight percent (based upon the total dry weight of phosphates present), and preferably at least about 0.1 weight percent, should be utilized. In extreme cases, such as when using the short chain polymers in tripolyphosphate mixtures containing relatively large proportions of the Form I modification, as much as 1 percent or more of the polymeric phosphate may be required. More than 10 percent will seldom be required, and under most circumstances 5 percent will be more than adequate.

As indicated above, a preferred embodiment of the present invention is the preparation of tripolyphosphate or pyrophosphate compositions into which the water-soluble linearly polymeric phosphates have already been incorporated. One of the simplest ways to prepare such a composition is by finely grinding or otherwise comminuting the polymeric phosphate and intimately intermixing it with the granular or powdered sodium tripolyphosphate or pyrophosphate. Another way to form such a composition with the polymeric phosphate intimately and uniformly distributed throughout the bulk of the tripolyphosphate or pyrophosphate is to form a solution of the polymeric phosphate in a volatile solvent, such as water or an alcohol-water mixture, and then to spray the solution onto or into a bed of the other phosphate. The solvent is evaporated from the bed, thereby precipitating the polymeric phosphate within the bed of tripoly- or pyrophosphate. It is particularly advantageous to maintain the temperature of bed of phosphate above the boiling point of the solvent in which the polymeric phosphate is dissolved. In this way, the solvent is evaporated very quickly upon contact with the phosphate bed, and there is less tendency for the solvent to dissolve any of the tripoly- or pyrophosphate and cause clumping, agglomerating, etc.

Another way of preparing suitable phosphate compositions containing small amounts of linearly polymeric phosphates is by exposing sodium tripolyphosphate to an elevated temperature for a relatively short period of time in order to fuse a small amount of the material on the surface of the tripolyphosphate particles. The fusion of tripolyphosphate results in the formation of solid pyrophosphate and molten linearly polymeric phosphates having an average chain length somewhat above 3. While equilibrium cooling of the fused tripolyphosphate would result in the reconversion of the pyrophosphate and linear polymers to tripolyphosphate, a relatively rapid cooling will trap the linearly polymeric materials in a non-equilibrium glassy state, thus giving the desired tripolyphosphate composition containing a small amount of the linearly polymeric phosphate of chain length longer than 3.

The phosphate compositions into which the linearly polymeric phosphates have been incorporated are utilized in the preparation of crutcher mixes (or slurries) or spray drying in substantially the same general manner that the phosphate builders have been utilized in the past. However, a higher concentration of solids can be utilized in slurries of the present phosphate compositions without increasing the viscosity of the slurry, or alternatively, the viscosity of the slurry can be markedly decreased without decreasing the concentration of solids in the slurry.

As an alternative to incorporating the polymeric additives into the slurry as an integral component of a phosphate builder composition, the additives can be incorporated into the aqueous slurries independently of the phosphate "builder" addition. If added independently, however, the linearly polymeric phosphates should

be added to the slurry prior to, or at least substantially the same time as, the phosphate builder is added. If added much later, substantial precipitation and crystallization of the hydrated phosphate will have taken place before the linearly polymeric material has an opportunity to delay such crystallization.

The term "linear," or "non-cyclic," as used herein with respect to the present polymeric phosphates, includes branched as well as "normal" chain phosphate polymers, but excludes the cyclic phosphates such as the trimetaphosphates. The ammonium polyphosphates, and especially those in which oxygen atoms have been replaced by imido nitrogen atoms, are examples of linear polyphosphates believed to have branched chains.

Further information and details relative to the practice of this invention may be gained by reference to the following examples, which also serve to demonstrate the marked advantages to be gained by the practice of the invention.

Example 1

Fifty grams of 95 percent glycerine and 50 g. of powdered sodium tripolyphosphate (2.4 weight percent STP-I, remainder STP-II) were thoroughly intermixed in a 200 ml. tall form beaker. Twenty-five milliliters of water was then added to the mixture and vigorously stirred for about 2 minutes. The resulting mixture was then allowed to stand for about 30 minutes. After this time the beaker was inverted, but the consistency of the mixture had increased to such an extent that only a few drops of liquid ran out of the beaker. A parallel test carried was out in the same manner, except that 0.5 g. of glassy sodium polyphosphate having an average chain length of about 5.5 was dissolved in the 25 ml. of water prior to mixing with the glycerine-sodium tripolyphosphate mixture. In this latter case, the entire slurry was readily poured from the beaker after the 30 minutes of standing.

Example 2

The procedure of Example 1 was duplicated, except that various water-soluble linearly polymeric phosphates in finely divided form were physically admixed with the sodium tripolyphosphate prior to incorporation into the glycerine. The results of these tests are summarized in the following table:

Sodium phosphate glass		Results of test
Concentration, in weight percent	Average chain length	
0	5.5	Slurry remained in beaker after inversion.
0.4	5.5	Very small proportion of solids remained after inversion.
0.5	5.5	Beaker completely emptied after inversion.
0.75	5.5	Do.
0.1	15.5	About $\frac{1}{8}$ " of solids remained in bottom of beaker after inversion.
0.4	15.5	About $\frac{1}{4}$ " of solids remained in bottom of beaker after inversion.
1.0	15.5	Beaker completely emptied after inversion.
0.02	112	About $\frac{1}{4}$ " of solids remained in bottom of beaker after inversion.
0.1	112	Beaker completely emptied after inversion.

Example 3

The procedure of Example 2 was duplicated, except that the water-soluble linearly polymeric phosphate used was a crystalline potassium polyphosphate having an average chain length of about 630. This polyphosphate, commonly known as Kurrol's salt, was utilized in a concentration of about 0.1 percent by weight, based upon the sodium tripolyphosphate. After the 30 minutes' standing period, most of the slurry could be readily poured from the beaker—only about $\frac{3}{4}$ of an inch of solids remaining in the bottom of the beaker.

Example 4

The procedure of Example 2 was duplicated, except that the water-soluble linearly polymeric phosphate was an ammonium polyphosphate of the type described by 5 Van Wazer in "Encyclopedia of Chemical Technology," vol. X, The Interscience Encyclopedia, Inc. (1953), pp. 419-20. The specific ammonium polyphosphates used were reaction products of ammonia, P_2O_5 , and water in the respective molar proportions of (A) 2.02/1.00/1.29 and (B) 2.91/1.00/0.49. Sample A had an 10 average chain length of about 12 P-atoms and a water-solubility of about 4 weight percent. Sample B had an average chain length of about 8 P-atoms and a water 15 solubility of about 60 weight percent. (The chain lengths were determined by the well known end-group titration method.) The results obtained by mixing various concentrations of these ammonium polyphosphates with sodium tripolyphosphates are summarized in the following table:

Concen- tration, in weight percent	Com- position	Ammonium poly- phosphate glass		Results of test
		None	In weight percent	
30	(A).....	0.01	Slurry remained in beaker after inversion.	About $\frac{1}{8}$ " of solids remained in bottom of beaker after inversion.
	(A).....	0.02	Slurry remained in beaker after inversion.	
	(A).....	0.1	Slurry remained in beaker after inversion.	
	(A).....	0.2	Beaker completely emptied after inversion.	
35	(B).....	0.2	Slurry remained in beaker after inversion.	About $\frac{1}{4}$ " of solids remaining in bottom of beaker inversion.
	(B).....	0.5	Slurry remained in beaker after inversion.	

Example 5

40 The test procedure of Example 2 was duplicated except that the water-soluble linearly polymeric phosphate was formed upon the surfaces of the sodium tripolyphosphate particles by briefly passing a flame over the surface of a mass of tripolyphosphate. After mixing 45 and allowing to stand as described in the foregoing examples, the slurry formed from the flame-treated tripolyphosphate was readily poured from the beaker, whereas the slurry prepared from an identical tripolyphosphate sample without flame treatment had increased 50 in viscosity to such an extent that none of the slurry could be poured from the beaker.

Example 6

55 The procedure of Example 2 was duplicated, except that tetrasodium pyrophosphate was substituted for the sodium tripolyphosphate. As in the cases where sodium tripolyphosphate was used, the slurry prepared from tetrasodium pyrophosphate without any water-soluble linearly polymeric phosphates became so thick that it 60 could not be poured from the beaker. However, when either 5 percent of a water-soluble linearly polymeric sodium phosphate having an average chain length of 5.5, or 0.5 weight percent of a water-soluble linearly polymeric sodium phosphate having an average chain length 65 of 15.5 was added to the tetrasodium pyrophosphate, the resulting slurry retained sufficient fluidity to be poured easily from the beaker.

Example 7

70 A solution of sodium tripolyphosphate super-saturated with respect to sodium tripolyphosphate hexahydrate was prepared by adding 340 g. of anhydrous sodium tripolyphosphate (about 2.5 weight percent Form 1) to 1000 ml. of water. The mixture was stirred for ten minutes, 75 cooled to 25° C. and filtered. To a 100 ml. portion of

the filtrate, there were added (1) 0.6 g. of a sodium phosphate glass having a known average chain length and (2) 10 g. of recrystallized sodium tripolyphosphate hexahydrate. (The latter was added to provide a surface for crystallization of the hexahydrate from the solution.) The resulting mixture was continuously stirred while sodium tripolyphosphate hexahydrate crystallized from the solution. The rate of crystallization was determined by periodically withdrawing samples of the supernatant liquid and determining the dissolved solids concentration therein. Two other 100 ml. portions of filtrate were treated in the same manner except that sodium polyphosphate glasses of different average chain lengths were used. A fourth portion of filtrate was used as a control, being treated in the same manner as each of the others except that no polyphosphate glass was added. The results of the foregoing tests are set forth in the drawing in the form of a plot of the amount of sodium tripolyphosphate hexahydrate crystallized from the solution, as a function of time and average chain length of the sodium polyphosphate glasses added to the solution. From this plot it can be seen that the rate of crystallization from solutions of the less highly condensed phosphates, such as tetrasodium pyrophosphate and sodium tripolyphosphate, is markedly decreased by small amounts of water-soluble linearly polymeric phosphates, such as the sodium phosphate glasses.

I claim:

1. An anhydrous intimately intermixed physical admixture of anhydrous sodium tripolyphosphate containing less than 10 weight percent of sodium tripolyphosphate-I, and between about 0.01 weight percent and about 10 weight percent of a water-soluble linearly polymeric phosphate salt having a chain length greater than 3.

2. An anhydrous intimately intermixed physical admixture of anhydrous sodium tripolyphosphate containing less than 10 weight percent of sodium tripolyphosphate-I, and between about 0.1 weight percent and about 10 weight percent of a water-soluble linearly polymeric alkali metal phosphate salt having a chain length greater than 3.

3. A composition consisting essentially of anhydrous sodium phosphates and made up of an intimately intermixed physical admixture of anhydrous sodium tripolyphosphate containing less than 10 weight percent of sodium tripolyphosphate-I, and between about 0.1 weight percent and about 5 weight percent of a mixture of water-soluble linearly polymeric sodium phosphates having an average chain length greater than about 5.

4. A process for producing an anhydrous sodium tripolyphosphate composition which slowly hydrates in and crystallizes from aqueous solutions thereof, which process comprises spraying an aqueous solution of a water-soluble linearly polymeric phosphate salt having a chain length greater than 3 upon a heated granular mass of anhydrous sodium tripolyphosphate while maintaining the temperature of said granular mass above the boiling point of the solvent in said linearly polymeric phosphate salt solution, the amount of said linearly polymeric phosphate salt being between about 0.01 weight percent and about 10 weight percent of the total dry weight of tripolyphosphate and linearly polymeric phosphate salt.

5. A process for producing an anhydrous sodium tripolyphosphate composition which slowly hydrates in and crystallizes from aqueous solutions thereof, which process comprises spraying an aqueous solution of a mixture of water-soluble linearly polymeric sodium phosphate salts having an average chain length greater than about 5 upon a heated granular mass of anhydrous sodium tripolyphosphate while maintaining the temperature of said mass above 100° C., the amount of said linearly polymeric sodium phosphate salt being between

about 0.01 weight percent and about 10 weight percent of the total dry weight of tripolyphosphate and linearly polymeric sodium phosphate salt.

6. In the process of utilizing anhydrous sodium tripolyphosphate in preparing aqueous detergent slurry composition suitable for spray-drying to a dry detergent composition containing sodium tripolyphosphate as a builder therein the improvement which comprises separately incorporating into said slurry between about 0.01 weight percent and about 10 weight percent, based upon the total phosphates in said slurry, of a mixture of water-soluble linearly polymeric phosphates having an average chain length greater than 3.

7. In the process of utilizing anhydrous sodium tripolyphosphate in preparing an aqueous detergent slurry composition suitable for spray-drying to a dry detergent composition containing sodium tripolyphosphate as a builder therein, the improvement which comprises increasing the fluidity of said slurry by adding said anhydrous sodium tripolyphosphate to said slurry as an intimately intermixed physical admixture with between about 0.01 weight percent and about 10 weight percent of a mixture of water-soluble linearly polymeric sodium phosphate salts having an average chain length greater than 3.

8. In the process of utilizing anhydrous sodium tripolyphosphate in preparing an aqueous detergent slurry composition suitable for spray-drying to a dry detergent composition containing sodium tripolyphosphate as a builder therein, the improvement which comprises increasing the fluidity of said slurry by utilizing said anhydrous sodium tripolyphosphate in the form of a particulate mass having between about 0.01 weight percent and about 10 weight percent of a mixture of water-soluble linearly polymeric phosphate salts with average chain length greater than 3 intimately dispersed upon the surfaces of said anhydrous sodium tripolyphosphate by precipitation from an aqueous solution of said linearly polymeric phosphates at a temperature in excess of 100° C.

9. The method of retarding crystallization of hydrated sodium tripolyphosphate from supersaturated aqueous solutions formed by dissolving anhydrous sodium tripolyphosphate in water, which method comprises adding to said water prior to incorporation of said anhydrous sodium tripolyphosphate a minor but effective crystallization-retarding concentration less than about 10 weight percent, based upon the total phosphates, of a mixture of water-soluble linearly polymeric phosphates having chain lengths in excess of 3, the predominant water-soluble linearly polymeric phosphate salt in said mixture having a chain length greater than 5.

10. The method of retarding crystallization of hydrated sodium tripolyphosphate from supersaturated aqueous solutions formed by dissolving anhydrous sodium tripolyphosphates in water, which method comprises adding to said water prior to incorporation of said anhydrous sodium tripolyphosphate a minor but effective crystallization-retarding concentration between about 0.01 weight percent and about 10 weight percent, based upon the total phosphate, of a mixture of water-soluble linearly polymeric phosphate salts having chain lengths in excess of 3, the predominant water-soluble linearly polymeric phosphate salt in said mixture having a chain length greater than 6.

11. The method of retarding crystallization of hydrated sodium tripolyphosphate from supersaturated aqueous solutions formed by dissolving anhydrous sodium tripolyphosphate in water, which method comprises adding to said water prior to incorporation of said anhydrous sodium tripolyphosphate a minor but effective crystallization-retarding concentration between about 0.1 weight percent and about 5 weight percent, based upon the total phosphate, of a mixture of water-soluble linearly polymeric phosphate salts having chain lengths in excess of 3, the predominant water-soluble linearly polymeric

phosphate salt in said mixture having a chain length greater than 7.
